REFLECTOR DEVICE

Oliver C. Ritz-Woller, Chicago, Ill.

Application January 19, 1935, Serial No. 2,479

9 Claims. (Cl. 88—82)

My invention relates to reflector devices and particularly to a form of device adapted for use on the sides and ends of a truck in position to catch the rays from the headlights of an oncoming car and reflect such rays backwardly to the driver of such oncoming car for a warning as to the presence of the truck on or near the highway. It is one of the objects of my invention to provide a new and improved form and arrangement of parts comprising a reflector device of this type so arranged and constructed as to give improved results with respect to the initial efficiency of the device for directing a ray backwardly toward its source, with respect to its 15 sturdiness and its degree of protection against breakage or distortion under the exceedingly hard conditions of use on a truck, and with respect to its protection against either temporary or permanent deterioration as a reflector by reason of the 20 presence of moisture.

To these ends, it is one of the objects of my invention to provide such an improved arrangement of parts as to insure facility of manufacture whereby a high degree of precision may be attained in manufacture of the devices upon a 25 commercial scale without unduly increasing the cost of the article. It is another object of my invention to provide an improved combination of cooperating rigid parts and resilient parts which 30 shall be effective for housing the lens portions and protecting them from breakage, which shall continue to hold the parts in cooperative relation even if the housing may be distorted from its original condition, and which may be relied upon 35 for keeping out moisture under any and all weather conditions.

It is another object of my invention to improve devices of this type in sundry details hereinafter pointed out. The preferred means by 40 which I have accomplished my several objects are illustrated in the drawings and are hereinafter specifically described. That which I believe to be new and desire to cover by Letters Patent is set forth in the claims.

45 In the drawings:—

Fig. 1 is a front face view of the preferred form of my device;

Fig. 2 is a central vertical section taken at line 2—2 of Fig. 1;

50 Figs. 3, 4, and 5 are sectional views through portions of isolated parts of the device for better showing their construction;

Fig. 6 is a cross sectional view through a portion of the front pad of the device with a lens 55 in position opposite one of the openings through

the pad and another lens in position within an opening for showing the relative sizes of the parts;

Fig. 7 is a front face view of a modified form of construction; 5

Fig. 8 is a central vertical section taken on line 8—8 of Fig. 7;

Fig. 9 is a vertical sectional view through a fragmentary portion of the device as shown in Fig. 8 but showing the parts in a preliminary 10 position; and

Figs. 10 and 11 are perspective views of two of the elements of the structure shown separately for clearness of illustration.

Referring now to Figs. 1 to 6 inclusive, in 15 which corresponding parts are indicated by the same reference characters, 15 indicates a casing member formed of sheet metal having a plurality of openings 16 in its front face, in the arrangement shown the casing member being pressed into 20 form out of sheet metal. Immediately in rear of the front wall of the casing member 15, I have provided a pad 17 of sponge rubber provided with a plurality of openings 18 therethrough in positions corresponding to those of the openings 16 25 in the front face of the housing member 15. In the openings 18 of the pad 17, I have provided a series of substantially spherical lenses 19, such lenses 19 being of substantially greater size than that of the openings 18 whereby it is necessary 30 to stretch the rubber about the openings somewhat for the insertion of the lenses into position. The pad 17 is preferably molded complete with the openings 18 therethrough.

The lenses 19 are preferably formed of glass 35 of the desired color, being formed originally of substantially spherical form and being then given a high polish by well-known methods, which can be accomplished readily and cheaply with a high degree of success. The lenses 19 produced upon 40 a commercial basis are of a high degree of accuracy as to their spherical form and are very hard so as to withstand a hard blow from a hammer or the like without breakage.

In the arrangement shown, I have provided 45 a plate 20 in rear of the pad 17 and the lenses 19, the plate 20 being provided with openings in positions corresponding to those in the front wall of the casing, the openings in the plate 20 being of such size as to insure that the pad 17 shall 50 be compressed somewhat between the plate 20 and the front wall of the casing when the plate 20 is pressed forwardly in the casing into engagement with the lenses 19. In rear of the retainer plate 20, I have provided a spacer member which 55

in the arrangement shown is in the form of a plate 21 having a series of openings 22 therethrough, the metal around the openings 22 being pressed into oblique position so as to provide flanges 23 about the openings by which the effective thickness of the plate is increased. In rear of the spacer member 21, I have provided a reflector 24 which in the construction illustrated is in the form of a disc of polished aluminum or chromium having forwardly concaved portions 25 arranged about the face of the member in positions corresponding to the positions of the lenses 19. The curvature of the concaved portions 25 and the effective thickness of the spacer member 21 are such that the concaved portions are concentric with respect to the spherical lenses 19. For holding the spacer member 21 and the reflector 24 in position with respect to each other, I have provided lugs 26 on the plate 20 which extend through suitable openings 27 and 28 in the spacer member and the reflector for preventing any substantial relative movement between the parts.

In the casing 15 in rear of the reflector 24, I have provided a pad 29 of sponge rubber of such thickness that it normally extends some little distance beyond the rear face of the casing member 15. In rear of the pad 29, I have provided a sheet 30 of rubber and a metal plate 31 which are held in position with respect to the casing member 15 by means of a flange 32 carried by the casing member, the flange 32 being connected with the plate 31 by means of rivets 33 which in the arrangement shown are in the form of integrally formed grommets. The arrangement is such that when the back plate 31 is pressed into closure position the marginal portion of the sheet 30 acts as a gasket for providing a moisture-tight closure of the rear face portion of the housing or casing. The pad 29 is also substantially compressed so as to apply substantial pressure forwardly upon the reflector 24, the spacing member 21, and the plate 20 so as to bring the plate 20 into tight engagement with the rear face portions of the lenses 19, whereby the pad 29 is compressed forwardly in addition to the compression produced laterally by the insertion of the lenses 19. The result is that an effective moisture-tight closure is produced between the front wall of the casing and the lenses 19.

With the lenses 19 of highly accurate spherical form as produced upon a commercial basis rather than by a precision process, with the rear face portions of the lenses and the front face of the reflector protected against the presence of moisture, and with the reflector accurately formed and accurately positioned concentrically with respect to the lenses, my device is highly efficient for the purpose for which it is provided. I have found in practice that a large proportion of the ray of light striking the front face of the reflector is returned to the source of light with only a fair degree of spreading of the ray such as is desirable for making the device effective as a warning signal. My construction is such that a heavy blow can be applied to the lenses without breakage, the resilient mounting of the lenses being such as to cushion the blow and prevent substantial damage.

My improved device as above described is so arranged and so organized that the parts can be produced readily and cheaply, and the assembly can be effected very rapidly by unskilled labor.

Referring now to the construction shown in

Figs. 7 to 11, 34 indicates a casing member similar to the casing member 15 having openings 35 in its front face. Immediately in rear of the front wall of the housing or casing member 34, I have provided a sheet of rubber 36 provided with openings 37 therethrough corresponding in position to the positions of the openings 35 in the front wall of the casing member, such openings 37 being of considerably smaller size, however, than that of the openings 35. In rear of the sheet of rubber 36, I have provided a plurality of substantially spherical lenses 38 similar to the lenses 19 above described, the arrangement being such that when the forwardly tapered front portions of the lenses 38 are pressed forwardly so as to extend through said openings 35 and 37 into the position as shown in Fig. 8 the marginal portions of the sheet of rubber about the openings 37 are turned forwardly into the form of flanges 39 which serve as resilient seats for the lenses 38 in the openings 35. The arrangement is such that when the lenses 38 and the rubber member 36 are pressed forwardly a moisture-tight closure is effected between the lenses and the front wall.

In rear of the lenses 38, I have provided a plate 40 having openings 41 therethrough corresponding in position to the position of the openings 35 in the front wall of the casing member. In rear of the plate 40, I have provided a reflector plate 42 which in the arrangement shown is formed of aluminum and highly polished on its front face. As is clearly shown in Fig. 11, the plate 42 is provided with a series of forwardly concaved portions 43 corresponding in relative position to the positions of the lenses 38 so that the concaved portions 43 are adapted to fit over the rear end portions of the lenses. In rear of the reflector, I have provided a compressible pad 44 which in the arrangement shown is made of sponge rubber, the pad being of such thickness as normally to extend backwardly out of the casing member 34. About the pad 44 on the rear face of an outwardly extending flange 45 of the housing or casing 34 I have provided a washer 46 of sheet rubber which is held in position by a back plate 47. As will be readily understood, the pad 44 is compressed substantially by the attachment of the back plate 47 in position. In the arrangement shown, the plate 47 is held in position by rivets 48 formed integrally with the flange 45 in the form of grommets.

As will be readily appreciated from an examination of my improved construction, the reflector is held positively in backwardly spaced relation to the lenses at all times, the arrangement being such that one of the lenses and the reflector may be pushed backwardly together under heavy pressure without changing the backwardly spaced relation of the reflector with respect to the lenses, the resilient support for the reflector (the pad 29 or the pad 44 in the arrangement shown) being adapted to yield for permitting this result. Upon the removal of the backward pressure from the lens, the resilient support serves to move the reflector and the lenses quickly forward again into normal position with respect to the casing. If the backward movement of the parts with respect to the casing has been such as temporarily to destroy the moisture-tight closure between the casing and the lenses, such moisture-tight closure is promptly re-established upon the return movement of the parts.

It will be appreciated that the retainer plate 20 (or the retainer plate 40) which is of comparatively heavy sheet metal formation serves

as a reinforcement for the metal reflector, acting to prevent bending of the reflector when backward pressure is applied upon one or more of the lenses without a corresponding pressure upon the remaining lenses. The arrangement is such that when the abnormal backward pressure is relieved upon the lenses the parts are brought back to normal operative position without distortion or disarrangement otherwise.

10 While I prefer to employ the form and arrangement of parts as illustrated in my drawings and as above described, it is to be understood that my invention is not to be limited to such form and arrangement except so far as the claims 15 may be so limited by the condition of the prior art.

I claim:

1. In a device of the type described, the combination of a casing member having an opening 20 in its front wall portion, a lens having a forwardly tapered portion extending through said opening, a member of yielding resilient material surrounding the forwardly tapered portion of said lens and compressed edgewise of the wall 25 between the tapered portion of the lens and the edge of the wall surrounding said opening when said lens and said resilient member are pressed forwardly, and means for holding said lens yielding in position and for tightly closing the casing 30 in rear of the lens for preventing the entrance of water and comprising a comparatively thick pad of yielding resilient material in rear of said lens adapted when pressed forwardly to apply forward pressure on said lens and said resilient member and adapted under normal conditions to permit a substantial backward yielding movement of said lens, and means for holding said pad compressed for normally applying forward pressure on said lens and said resilient member so as to hold said resilient member also compressed.

2. In a device of the type described, the combination of a casing member having a series of circular openings in its front wall portion, a member formed of resilient yielding material in 45 position in said casing member adjacent to said front wall portion and having openings therein in centered registering position with respect to the openings in said front wall portion, substantially spherical lenses seated in said openings in 50 said resilient yielding member with their forwardly tapered portions extending through the openings in said front wall portion and serving when pressed forwardly to compress said resilient yielding member at the marginal portions thereof about said openings between said forwardly tapered portions of the lenses and said front wall portion, a reflector member in backwardly spaced relation to said lenses, means for applying yielding pressure forwardly on said reflector member for pressing said lenses forward 55 whereby an effective seal is produced adapted normally to prevent the entrance of moisture between the lenses and said front wall portion and whereby said lenses are cushioned with respect to backward movement in the casing member, and means adapted by cooperation with the above mentioned parts to provide a watertight seal for said casing member in rear of said lenses for preventing the entrance of moisture from the 60 rear to the lenses.

3. In a device of the type described, the combination of a casing member having a plurality of circular openings in its front wall portion, a substantially spherical lens seated in each of 65 said openings and of substantially greater di-

ameter than that of the openings so as to be held by the wall portion in position with the major portion of the lens in rear of said front wall portion, a comparatively thick pad of yielding material having openings therethrough corresponding in position to the openings in said front wall portion with the lenses positioned in the openings in the pad so that the pad engages the major part of the side wall portions of each of the lenses with parts of the pad substantially compressed transversely between adjacent lenses, a reflector member in backwardly spaced relation to said lenses, and means for applying forward pressure on said reflector and lenses and pad so as to compress the pad against the lenses and against the front wall portion of the casing and for sealing the face of the casing member in rear of said reflector so as to prevent the entrance of moisture into contact with the front face of the reflector.

4. In a device of the type described, the combination of a casing member having a plurality of circular openings in its front wall portion, a substantially spherical lens seated in each of said openings and of substantially greater diameter than that of the openings so as to be held by the wall portion in position with the major portion of the lens in rear of said front wall portion, a comparatively thick pad of yielding material having openings therethrough corresponding in position to the openings in said front wall portion with the lenses positioned in the openings in the pad so that the pad engages the major part of the side wall portions of each of the lenses with parts of the pad substantially compressed transversely between adjacent lenses, a reflector member in rear of said lenses, means interposed between said reflector member and said lenses adapted when pressed forwardly by pressure on the reflector to press the lenses forwardly in fixed forwardly spaced relation to the reflector and to compress the pad against the lenses and against the front wall portion of the casing for preventing the entrance of moisture between the wall portion and the lenses, a second 45 comparatively thick pad of yielding material in said casing in rear of said reflector, and means for closing the rear face of said casing member and pressing said second pad forwardly for preventing the entrance of moisture into contact 50 with said reflector.

5. In a device of the type described, the combination of a casing member having a circular opening in its front wall portion, a sheet of flexible material in rear of said wall portion having an opening therethrough of smaller size than that in said wall portion, a lens seated in the openings in said wall portion and said sheet and of substantially greater size transversely than the opening in said wall portion so as to limit the 60 forward movement of the lens with respect to the wall portion for keeping the major portion of the lens in rear of said wall portion and for pressing forward the marginal portion of said sheet about the opening in the sheet in the form 65 of an annular flange between the lens and the wall, and means for applying yielding forward pressure on said lens to compress said sheet and for sealing the rear face of the casing member so as to prevent the entrance of moisture into contact with the rear portion of the lens.

6. In a device of the type described, the combination of a casing member having a series of circular openings in its front wall portion, a sheet of rubber in said casing member adjacent 75

to said front wall portion and having openings therein in correspondingly centered positions but of smaller size than the openings in said front wall portion, lenses seated in said openings having forwardly tapered portions extending through the openings so as to force the marginal portions of said sheet about said openings forwardly in the form of flanges between the lenses and the front wall portion, and means for applying yielding pressure forwardly on said lenses so as to compress said sheet and for sealing the rear face of the casing member so as to prevent the entrance of moisture into contact with the rear portions of the lenses.

15 7. In a device of the type described, the combination of a casing member having a series of circular openings in its front wall portion, a sheet of rubber in said casing member adjacent to said front wall portion and having openings therein in correspondingly centered positions but of smaller size than the openings in said front wall portion, substantially spherical lenses seated in said openings with their forward portions extending through the openings so as to force the 20 marginal portions of said sheet about said openings forwardly in the form of flanges between the lenses and the wall, and means for applying yielding pressure forwardly on said lenses so as to compress said sheet of rubber and for sealing the rear face of the casing member so as to prevent the entrance of moisture into contact with the rear portions of the lenses.

25 8. In a device of the type described, the combination of a casing member having a series of circular openings in its front wall portion, a sheet of rubber in said casing member adjacent to said front wall portion and having openings 30 therein in correspondingly centered positions

but of smaller size than the openings in said front wall portion, lenses seated in said openings having forwardly tapered portions extending through the openings so as to force the marginal portions of said sheet about said openings forwardly in the form of flanges between the lenses and the front wall portion, a reflector member in 5 backwardly spaced relation to said lenses, and means for applying yielding pressure forwardly on said reflector member for 10 pressing said lenses forward so as to compress said sheet of rubber and for sealing the rear face of the casing member so as to prevent the entrance of moisture into contact with the front 15 face of the reflector.

9. In a device of the type described, the combination of a casing member having a series of circular openings in its front wall portion, a sheet of rubber in said casing member adjacent to said front wall portion and having openings 20 therein in correspondingly centered positions but of smaller size than the openings in said front wall portion, substantially spherical lenses seated in said openings with their forward portions extending through the openings so as to force the 25 marginal portions of said sheet about said openings forwardly in the form of flanges between the lenses and the wall, a reflector member in said casing member having forwardly concaved portions in 30 backwardly spaced relation to the respective lenses in concentric relation thereto, and means for applying yielding pressure forwardly on said reflector member for pressing said lenses forwardly so as to compress said sheet of rubber and for sealing the rear face of the casing 35 member so as to prevent the entrance of moisture into contact with the front face of the reflector.

OLIVER C. RITZ-WOLLER.
